UNITED STATES PATENT OFFICE.

JOHN W. MEAKER, OF PHILADELPHIA, PENNSYLVANIA.

FASTENING FOR BAGS, POCKET-BOOKS, &c.

SPECIFICATION forming part of Letters Patent No. 276,852, dated May 1, 1883.

Application filed February 27, 1883. (No model.)

To all whom it may concern:

Be it known that I, JOHN W. MEAKER, a citizen of the United States, residing in the city and county of Philadelphia, State of Pennsylvania, have invented a new and useful Improvement in Fastenings for Bags, Pocket-Books, &c., which improvement is fully set forth in the following specification and accompanying drawings, in which—

10. Figure 1 is a side elevation of a fastening for a bag embodying my invention. Figs. 2 and 3 show the fastening as applied to pocket-books. Fig. 4 is a side elevation of a modification. Fig. 5 is a side elevation of another modification, partly sectional. Fig. 6 is a section of a portion in line *v v*, Fig. 1. Fig. 7 is a section of a portion in line *w w*, Fig. 2. Fig. 8 is a section of a portion in line *x x*, Fig. 3. Fig. 9 is a top view of a portion of Figs. 4 and 5. Fig. 10 is a section in line *y y*, Fig. 4. Fig. 11 is a section in line *z z*, Fig. 5. Fig. 12 is a section of a portion in line *v' v'*, Fig. 1.

Similar letters of reference indicate corresponding parts in the several figures.

25. My invention consists of the jaws of a bag, pocket-book, &c., having an additional jaw to which part of a fastening device is applied, and which by its yielding nature causes the secure engagement of said device with another fastening part or device on the bag, &c., the jaws of the bag, &c., being generally termed the "frame" of the same.

Referring to the drawings, *A A'* represent the jaws of a bag or pocket-book, to which the body of the bag or book is riveted or otherwise secured, as usual.

35. *B* represents an additional jaw, which is pivoted to the ends of the jaws *A* at the place of pivoting the two jaws *A A'* to each other, or, if desired, above said place, said jaw *B* inclosing the jaws *A A'*, and having a motion independent thereof.

To the under side of the jaw *B*, at the center thereof, is secured a clip, *C*, which extends transversely, so as to overhang the jaws *A A'*, the outer end of said clip having a nose, *a*, which is adapted to engage with the jaw *A*, as more clearly shown in Figs. 6, 7, and 8.

When the bag or book is opened and is to be closed, the jaw *A'* and jaw *B* are moved to-

gether toward the jaw *A*, and when the clip *C* reaches said jaw *A* the nose *a* rides on the latter and causes the elevation of the clip, this being permitted by the elastic or yielding nature of the jaw *B*. As soon as the nose clears the edge of the jaw *A* the clip drops against said edge and causes the engagement of the jaws *A* and *B*, and consequently the locking of the jaws *A A'*, thus holding the bag or book securely closed.

In order to open the book, the jaw *B* is forced away from the jaw *A*, thus overcoming the holding-power of the clip and separating the jaws *A A'*.

In Fig. 1 the jaw *B* is on the outside of a bag, and in Fig. 2 on the outside of a pocket-book. In Fig. 3 the jaws are covered by the flap *b* of a pocket-book, and in all these cases the upper face of the jaw *B* is left smooth. Furthermore, the jaw *B* is applied in position after the body of the bag or book and jaws *B* are riveted or otherwise connected.

In Fig. 6, *c* represents a piece for contact of the forefinger in opening and closing the pocket-book.

In Fig. 7 a pin having a head or knob, *d*, is secured to the jaw *A'*, and passed freely through an opening in the side of the jaw *B*, the knob limiting the motion of said jaw *B* from said jaw *A*, and also forming a place of contact for the forefinger.

In Figs. 4 and 10 a divided plate, *B'*, with knobs *B''*, is employed, the two parts being secured to the two jaws *A A'*, respectively, at the central portions thereof, and raised from said jaws. A vertical opening, *e*, is formed in the jaw *A*, and a pin, *f*, secured to the jaw *A'* at a place coinciding with said opening *e*. When the jaws *A A'* approach, the pin *f* raises the jaw *A* until the opening *e* is just above said pin *f*; then the jaw *A* drops, the pin enters the opening, and the two jaws are locked.

In Figs. 5 and 11 two pins or studs *f* and two openings *e* are employed, the operation, however, being similar to that shown in Figs. 4 and 10. In these two cases, however, the two knobs *B''* are simply employed to open the jaws.

Where the jaws *A A' B* have a common pivot, each pivot may be double-ended, as

shown by the dotted figure at the left of Fig. 1, the jaws A A' being fitted on one end and the jaw B fitted on the other end, the central head or washer of the pivot separating the jaws A A' from the jaw B at the pivotal ends; but where the jaw B is pivoted independently of the jaws A A', separate pivots are evidently employed.

I am aware that it is not new to provide pocket-book frames with spring-catches and spring-clips, and therefore do not claim the same.

Having thus described my invention, what I claim as new, and desire to secure by Letters Patent, is—

1. A frame for a bag, pocket-book, &c., provided with an additional jaw of yielding nature, and a fastening device, substantially as and for the purpose set forth.

2. A frame for a bag, pocket-book, &c., formed of jaws, in combination with an additional jaw connected with said jaws, adapted to yield, and a fastening device, substantially as and for the purpose set forth.

3. A frame for a bag, pocket-book, &c., provided with an additional jaw of yielding nature, substantially as described, to which is attached a clip, substantially as and for the purpose set forth.

4. A frame for a bag, pocket-book, &c., provided with an additional jaw of yielding nature, substantially as described, and fastening-clip, in combination with a finger-piece, c, substantially as and for the purpose set forth.

JOHN W. MEAKER.
